UNITED STATES PATENT OFFICE.

WILLIAM E. WINE, OF TOLEDO, OHIO.

CAR-DOOR-LOCKING DEVICE.

Application filed January 23, 1922. Serial No. 531,197.

To all whom it may concern:

Be it known that I, WILLIAM E. WINE, a citizen of the United States of America, residing at Toledo, in the county of Lucas and State of Ohio, have invented certain new and useful Improvements in Car-Door-Locking Devices, of which the following is a specification.

My invention relates to new and useful improvements in car door locking devices and has for an object to provide a locking device wherein the latch member is pivotally supported by two arms, one of which is shorter than the other, so that the said member when actuated has a tilting movement as well as a swinging movement.

As is well known to those skilled in the art, drop bottom doors of freight cars are relatively easy to close with the exception of the last or final closing movement, due to the fact that some of the coal dust or other material carried in the car will wedge in along the hinged edge of the door so that relatively great force has to be used to finally close and lock the door.

With the present invention, comprising a latch member which is to be supported at its rear by a relatively short arm, and at its forward end by a relatively long arm, as the latch member is swung into position, its forward end not only engages the ledge formed on the door, but it also tips upwardly and thereby exerts great pressure on the door at the final or locking movement of the door.

Still other objects of the invention are to provide a lock for drop bottom doors of railway cars wherein a latch member capable of a swinging and tipping movement is designed to be securely fastened to the side of the car body, the latch member of which will engage the ledge on the car door, and after the arm has been swung into its final position, a dog will be jammed in and against one of the supporting arms, thereby holding the latch member in locked relation with the ledge on the door making it impossible for the door to accidentally open.

Still other objects of the invention are to provide a locking device that is relatively cheap to manufacture, compact in nature and easily and readily applied to the freight car.

With these and other objects in view, the invention consists in certain new and novel

arrangements and combination of parts as will be hereinafter more fully described and pointed out in the claims.

In the drawings showing a preferred embodiment of my invention

Fig. 1 is a view in elevation showing a fragmentary portion of the side of a car, a drop bottom door having a ledge formed near its free edge and the locking device in its locked position, the dotted lines showing the position to which the locking device swings and tilts when the door is to be opened.

Fig. 2 is a sectional view taken on line 2-2 of Fig. 1.

Referring now more particularly to the invention, a fragmentary portion 1 of a side of a car is shown, a bracket 2 which is secured to a center sill (not shown) to which in turn is hinged the drop bottom door 3 and across which, near its free edge and extending outwardly beyond the side thereof, is the angle iron 4.

Securely riveted to the side of the car and above the angle iron 4 is the base plate 5, which may have the bosses 6 at its corners, through which are passed rivets 7, while a reinforcing strip 8 may be attached to the inner side of the car to strengthen the car at this point.

A further boss 9 is formed on the plate 5 near its upper edge and on which is supported an arm 10 and held by a rivet 11, it being noticed that the bottom of the plate 5 is slightly cored so that the head of the rivet 11 may lie flush with the side of the car. The arm 10 is also cored and at the bottom is provided an opening 12. Also pivoted to the plate 5, and preferably in the lower right hand corner, is a further arm 13, which will be noticed is much shorter in length than the arm 10, this arm also being provided at its lower end with an opening 14.

A latch member 15 is supported by the two aforementioned arms, the said latch member being hollow so that the free ends of the two aforementioned arms may loosely fit therein, while two rivets 16 and 17 are provided which are passed through suitable openings formed in the latch member 15 and through the aforementioned openings 12 and 14 formed in the lower ends of the arms 10 and 13.

Preferably formed integrally with the latch member 15 and at a point where one

100

105

110

rivet passes through this member and the arm 13, is the boss 18, so that the same may be struck with a hammer or other instrument when desired to either force the latch member inwardly or outwardly as the occasion arises.

Also pivotally mounted at the top of the arm 13 and held by one of the rivets 7 is the dog 19 which is designed to be swung 10 to engage with the rear of the arm 10 when the said arm is in its forward position, thereby preventing any movement of this arm until the dog is released which also may be accomplished by striking a boss 20 formed on and near the upper end of the dog.

To limit the forward movement of the arm 10 a stop 21 is formed integrally with the plate 5, and this stop is in a line with 20 the inner end of the top leg of the angle 4 as clearly shown in Fig. 1.

When the door is in its closed and locked position the forward ends of the latch member 15 will fit snugly beneath the upper leg of the angle 4 and the dog 19 will be wedged against the rear of the arm 10, thus tightly holding the door in its closed and locked position.

To open the door, the dog will be swung 30 rearwardly as shown in the dotted lines and the latch member swung rearwardly also assuming the position shown in dotted lines; the front end dropping and the rear end raising. This tipping action is of greatest 35 importance when closing the door, as after the front or forward end of the latch member engages the angle iron 4, and from this point to its final or locked position, the forward end of the latch member will raise, 40 thus forcibly raising the door to its final and locked position.

From the foregoing it will be seen that I have provided a locking device wherein the latch member is so mounted that not 45 only does it swing into and out of position when operated, but furthermore, tips or tilts so that final pressure on the latch member will not only tend to lock the door, but force the same upwardly.

It will be seen that I have provided a 50 locking device for drop doors that is relatively simple, consisting of but few parts, easily operated and efficient in service. Also, I have provided a locking device that 55 will not only force the door to its locked position, but have provided means so that it will be impossible for the door to open unless the locking device is manually operated.

Many slight changes might be made in 60 the shape of the latch member, or the relative position of the arms without in any way departing from the spirit and scope of the invention.

Having thus described the same, what I

claim as new and desire to secure by Letters Patent is:

1. A car door locking device comprising a base, two arms pivotally mounted on said base, one of said arms being shorter than the other, a latch member pivotally secured to the lower ends of said arms, said latch member adapted to pass beneath a ledge on a car door, and means for holding the latch member in its forward position. 75

2. A locking device for railway cars comprising a base, two arms pivotally mounted on said base, one of said arms being shorter than the other, and the pivotal point of the short arm being below that of the pivotal point of the longer arm, a latch member pivotally secured to the lower ends of said arms adapted to engage a ledge on a car door to thereby support the door and means for locking the latch member in its forward 80 and locking position.

3. A locking device for car doors comprising a base, arms pivotally mounted on said base, the pivotal point of one arm being lower than the pivotal point of the other 90 arm, a latch member having an aperture therein, the said arms extending into said aperture and pivotally secured to said latch member, said latch member adapted to swing and tilt to engage a ledge formed on the car 95 door to thereby lock the same and means for locking the latch member in its forward and supporting position.

4. A car door locking device comprising a plate, two arms pivotally secured to the 100 said plate, one of said arms being shorter than the other and the pivotal point of one arm being below that of the other, a hollow latch member pivotally secured to the lower ends of said arms, the forward end of which 105 is adapted to pass beneath a ledge formed on the car door, means for limiting the forward movement of said arms and latch member and locking means for retaining said arms and latch member against a rearward movement. 110

5. In combination with a car, having a drop bottom door and a ledge on said door extending beyond the free side of the same, a locking device comprising a plate secured 115 to the side of the car and above said ledge on said door, a latch member pivotally secured to said plate and so arranged that when swung forwardly the forward end of the same will tilt upwardly to thereby force 120 the said door upwardly through the medium of said ledge on said door to a closed position and means for holding said latch member in engagement with said latch on said door.

6. In combination with a freight car having a drop bottom door, a ledge secured to said door and extending beyond the free side of the same, a locking device comprising a plate secured to the side of the car and 130

above said ledge, a latch member swingingly mounted on said plate and engaging said ledge when in a forward position, said latch member so arranged that it is capable of a 5 swinging and tilting movement during its travel from an unlocked to a locked position to thereby tightly force the door to a closed position, and means for retaining the latch member in engagement with the ledge on 10 said door to thereby prevent accidental opening of said door.

7. In combination with a car having a drop bottom door, a ledge formed on the door and extending beyond the free side 15 thereof, a locking device rigidly secured to the side of the car body and located above said ledge on said door, said locking device comprising a plate, a latch member carried by said plate and so swung from said plate that the forward end of said latch member 20 will tilt upwardly as said latch member is swung from an unlocked to a locked position, the said forward end of said latch member extending beneath the ledge on said door when in its forward position, a lug 25 formed on said latch member to provide a striking surface for operating the said latch member and means pivotally mounted on said plate for locking the latch member in engagement with the ledge on said door 30 to thereby hold the door in a tightly closed and locked position.

In testimony whereof I affix my signature.
WILLIAM E. WINE.
